A. A. KUCHER

REFRIGERATION

Filed April 7, 1922

Fig. 1.

UNITED STATES PATENT OFFICE.

ANDREW A. KUCHER, OF CHESTER, PENNSYLVANIA.

REFRIGERATION.

Application filed April 7, 1922. Serial No. 550,445.

This invention relates to the art of refrigeration and particularly to this art as practiced by means of the so-called compression process. An object of my invention is 5 to provide for a process of the character designated a novel working fluid which shall have as constituents a refrigerant and a lubricant admixing therewith to form a homogeneous fluid of such a character that 10 the lubricant is not mechanically segregated from the refrigerant in passing through a compression refrigeration cycle.

My invention has for a further object to provide, in a process of the character designated, a novel method and means for lubricating the compression mechanism which shall be effective during long periods of service without attention and without the necessity of employing separating mechanism for 20 freeing the refrigerant fluid from the lubricant.

A still further object of my invention is to provide a method and means for positively priming the compression mechanism 25 during the initial pumping operations thereof and thereafter to supply continuously adequate quantities of lubricant to seal the compression chambers and to lubricate the relatively moving and contacting surfaces 30 of the compression mechanism.

These and other objects, which will be made apparent throughout the further description of the invention, may be attained by the employment of the apparatus hereinafter described and illustrated in the accompanying drawing in which Fig. 1 is a view in longitudinal section illustrating a compression refrigerator in which my invention may be practiced; and Fig. 2 is a 40 view in transverse section through the pump of apparatus shown in Fig. 1.

Compression refrigerators nominally comprise a chamber in which a working fluid is evaporated at a relatively low pressure and 45 temperature, a chamber in which the vapors are condensed at a higher pressure and temperature, a compression mechanism for translating the vapors from the evaporation chamber to the condensing chamber, and a 50 valved conduit for returning the condensed fluid at a reduced pressure into the evaporation chamber. The cycle is continuous during any period of operation, heat being absorbed from the medium surrounding the 55 evaporation chamber to secure the desired refrigerating effect, which heat is removed

from the apparatus by bringing an outside medium into heat-exchanging relation to the contents of the condensing chamber. Apparatus of this character generally operates intermittently; for example, a period of operation of from one to one and a quarter hours being followed by a period of inactivity of from one and a half to two hours, the length of the periods depending upon the duty imposed upon the refrigerator and upon the setting of the automatic devices which control the starting and stopping of the compression mechanism.

In general, the compression mechanism is tightly encased to prevent escape of the working fluid and, for this reason, some means for the lubrication thereof must be provided which will operate without attention continuously and reliably for long periods of time, as for example, for one or more years. It is to this problem of effectively lubricating enclosed compression mechanism of compression refrigerators of the type above indicated that the present invention relates.

It has heretofore been proposed to employ in compression refrigerators a lubricant which is immiscible with the refrigerant. Many liquids possessing to a greater or less extent this property have been used, generally with incomplete success, since no combination of refrigerant and lubricant has been found in which the liquids do not mingle to some extent when brought together under the conditions of agitation obtaining in a compression refrigerator. Mechanical separators of various types have been employed in connection with machines of this character to facilitate the segregation of the lubricant and the refrigerant. This expedient has improved the operation but has not resulted in accomplishing sufficiently complete segregation of the fluids to enable compression refrigerators utilizing a compound working fluid of this character to operate for long periods without a replacement of the lubricant.

The purpose of the present invention is to provide a thoroughly satisfactory and reliable lubrication of the compression mechanism of a compression refrigerator. In accomplishing this result, I have departed radically from the prior attempts to employ an immiscible lubricant. I have discovered that by the employment of a working fluid comprising a refrigerant and a lubricant

which readily mix one with the other to form a homogeneous liquid or physical solution of a character that its constituents are mechanically inseparable, I am enabled to 5 overcome completely the lubrication difficulties heretofore experienced in the operation of compression refrigerators.

The term "mechanically inseparable" as used in the specification and claims of this 10 application is to be understood to include such admixtures of a refrigerant and a lubricant as do not separate out into segregated bodies or globules under the influence of gravity or of centrifugal action obtaining in 15 a compression refrigerator. In common with admixtures and solutions of this character, a vaporization of one or both of the constituents of my compound working fluid may be effected by temperature or pressure 20 changes thereof. The working fluid may thus be considered to consist of a very intimate admixture or a physical solution of its constituent parts.

In obtaining a working fluid of this 25 character, a wide range of refrigerants and lubricants may be employed. I have found by experiment that ethyl chloride as a refrigerant and a mineral oil as a lubricant, which will readily mix in suitable proportions 30 with ethyl chloride, very satisfactorily meet the required conditions for efficient refrigeration and lubrication. Good results have been obtained with a mixture of one part ethyl chloride to one or less parts of 35 mineral oil. The amount of lubricant required depends upon the type of the pump employed and upon the character of the lubricant utilized. One example of a lubricant which may be satisfactorily employed is a 40 filtered mineral oil having a viscosity of about 750 seconds at 100 degrees Fahrenheit, Saybolt universal viscometer, and a pour test of about zero degrees Fahrenheit. An oil of such a character may be mixed with ethyl 45 chloride in an approximate ratio of four parts of ethyl chloride to one part of oil. This admixture has been found under severe centrifugal tests to exhibit no tendencies to separate into its constituents and hence may 50 be said to constitute a true physical solution. A further example of refrigerant and lubricant constituents, which may form the working fluid of the present invention, comprises 55 an admixture of ethyl chloride, or other halogen derivative of the methane group of hydrocarbons, and colloidal carbon or graphite. It is to be understood, however, that my invention is in no way limited to the 60 employment of a working fluid having the particular constituents above mentioned, or to any specific proportions of the constituent refrigerants and lubricants.

It is a further purpose of my invention to 65 provide a novel method and apparatus for ensuring a sufficient lubricant supply to the

pumping mechanism for priming at the starting thereof and for continuously delivering to the pumping mechanism an adequate supply of lubricant during periods of operation. This is accomplished by collecting in the path of vapors to the pump a limited quantity of the working liquid which is drawn into the pumping mechanism upon the initial movements thereof, effecting a thorough priming. Small quantities of the 70 working liquid are continuously introduced into the stream of vapors flowing to the compression mechanism and pass through the working chambers with the vapors, sealing the chambers against leakage and lubricating all the wearing surfaces. 75

I show in the accompanying drawings a compression refrigerator in which my novel method of operation may be carried out. It is to be understood that this invention 80 may be practiced in other types of compression machines and that the apparatus illustrated and herein described is employed by way of example and as an aid in presenting 85 a clear exposition of my invention. 90

In the drawings, 10 designates a condensing chamber, below which is suspended an evaporation chamber 11. A vapor conduit 12 leads from the evaporation chamber into the condensing chamber, and a return pipe 13 serves to convey the condensed fluid to and from the condensing chamber 10 into the evaporation chamber 11. Interposed in the vapor conduit 12' and return pipe 13 is a compression mechanism 14, which may be of well known type, and driven by a motor 15 of suitable construction. A pressure reducing valve 16, controlled by a float 17, is also interposed in the return pipe 13. The above are the usual elements of a compression refrigerator which may in the practice of my invention be associated in a wide variety of arrangements. 100

As illustrated in the drawing, the condensing chamber 10 comprises a bell or dome 20 secured to a base plate 21, as by bolts 22. The base plate has formed integrally therewith a depending flange 23 upon which the machine is supported. The motor 15 is housed within a casing 24, which as shown is an inverted cup-shaped casting secured to the base plate 21. Mounted upon the casing 24 is a pump housing 25. A common shaft 26 serves both the motor and the pump, the lower end of the shaft being secured in a suitable bearing in the base plate 21 and an intermediate portion of the shaft in a journal bearing provided in top wall 27 of the casing 24. The wall 27 also forms the bottom wall of the pump housing and consequently 110 no bearing for the upper end of the shaft 26 is required. 120

The pump illustrated is of the type disclosed in my copending application, serially numbered 509,672, filed October 22, 1921, and 130

entitled Refrigeration machine. The housing 25 is provided with a cylindrical bore into which open an inlet port 31 communicating with the vapor conduit 13 and an outlet port 32 terminating in a check valve 32'. The inner bored surface of the housing is provided with longitudinally offset arcuate grooves 33 and 34, which intercept the ports 31 and 32, respectively. A cylindrical shell 35 closely fits the cylindrical bore of the housing 25 and is provided with oppositely-disposed longitudinally offset ports 36 and 37 that communicate respectively, with the grooves 33 and 34. A rotor or drum 38 is mounted upon the shaft 26, the rotor and shaft being eccentric with respect to the bore of the cylindrical housing 25. Radial slots 39 in the rotor 38 are adapted to receive slidably vanes 40 and 41, which divide the space formed by the eccentricity of the rotor 38 and the cylindrical shell 35 into chambers 43 and 44. The vane 40 is flexibly keyed to the cylindrical shell 35, as by a pin 45. Rods 46 extend through openings 47 in the rotor and openings 47 in the shaft into proximate relation to the inner edge of vanes 40 and 41. Springs 48 surround the rods and exert outward pressure against the vanes.

The upper and lower surfaces of the rotor vanes and of the cylindrical shell lie in two parallel planes, the lower surfaces seating against the top wall of the casing 24 and the upper surfaces seating against a disc or plate 50 which is free to rotate. The plate 50 is normally held in position by the pressure of the fluid in the chamber 20 but may have a pin 52 engaging the disc 50 at its central point and pressed to its seat by a spring 53. The shaft within the motor housing and above the motor has secured thereto a cup 56, which serves to catch the lubricant which works downwardly along the shaft from the pump housing. The rapid rotation of the cup throws the liquid collecting therein to the side of the casing, whence it flows to the bottom thereof and serves to lubricate the bearing. A vent port 57 opening into the vapor tube 12 permits the excess liquid to be carried therethrough into the pump.

Condensing coils 60 are arranged in the upper part of the dome 20 and are provided with inlet and outlet connections 61 and 62, which pass without the chamber 10 through the base plate 20. An electric cable 63 for furnishing current to the motor is also passed through a fluid tight plug 64 in the base plate 21.

The evaporation chamber 11, as shown, comprises a cylindrical tank, having a specially formed top or cap member 70. The vapor conduit 12 and the return pipe 13, enter the chamber 11 through the cap 70. The pipe 13 is shown within the conduit 12, an arrangement which reduces the number

of seals necessary in connecting the condensing and evaporating chambers. It is to be understood, however, that these conduits may be independent one of the other and that the invention is in no way dependent upon the arrangement of these connections.

The conduit 12 opens into a small chamber 72, in the cap member 70, from which an extension of the vapor conduit 73 depends, preferably in the form of any reverse flow passage such as a U-tube. The U-tube should extend downwardly well below the surface of the liquid and its free open end should terminate near the top of the evaporator chamber, for the reception of vapors. A small aperture 74 in the curved portions of the U-tube, below the normal level of the liquid contents of the evaporation chamber permits some of the liquid to enter the vapor conduit for the purpose of carrying the lubricant to the pump as more fully herein-after appears.

The operation of the apparatus thus described is as follows. The condensing chamber and the evaporation chamber are both filled to a level, such as indicated in the drawings, with a working fluid consisting of a suitably mixed refrigerant and lubricant. Prior to starting the motor, a quantity of the working liquid fills the U-tube 73 to the level of the liquid in the chamber 11. The first rotations of the pump draw this liquid into the pump so that a thorough priming of the moving parts is obtained during the initial operations thereof. The priming liquid not only lubricates the frictionally engaging surfaces but seals the working chambers of the pump against vapor leakage. As the rotation of the pump continues, vapors from the chamber 11 are drawn up through the conduit 12 into the pump and discharged therefrom into the chamber 20. A fine stream or spray of the liquid in the chamber 11 enters the U-tube through the aperture 74 and is commingled with the vapors flowing through the conduit 13 to the pump. The liquid thus delivered to the pump is sufficient in quantity to effect a thorough lubrication and sealing thereof and is supplied continuously so long as the pump is in operation. When a predetermined cooling action has resulted from the operation of the machine, automatic mechanism (not shown) cuts off the current to the motor and thus stops the pumping action. During the period of rest which follows, some of the liquid in the chamber 11 fills the lower portions of the U-tube 74, placing the mechanism in readiness for starting again.

The lubrication of the bearings of the shaft 26 is accomplished from the liquid delivered to the pump. Some of this liquid seeps down through the journal bearing in the wall 27 into the cup 56, thence it is thrown by centrifugal force to the side of the

motor housing and collects in the bottom thereof. A shallow pool of liquid is constantly maintained therein for lubricating the lower bearing of shaft 26, the excess being carried away through the vent 57 into the vapor conduit.

While I have shown my invention in but one form, it will be obvious to those skilled in the art that it is not so limited but is susceptible of various other changes and modifications, without departing from the spirit thereof and I desire, therefore, that only such limitations shall be placed thereupon as are imposed by the prior art or as are specifically set forth in the appended claims.

What I claim is:

1. In the process of refrigeration in which a liquid is evaporated in one chamber, the vapors pumped into another chamber and condensed therein at a higher pressure, and then returned to the first chamber at a reduced pressure, the method of lubricating the pumping mechanism which comprises employing a working fluid consisting of a refrigerant and a lubricant which forms therewith a mechanically inseparable homogeneous mixture, introducing portions of the working fluid into the stream of vapors during their passage to the pumping mechanism and passing the commingled working fluid and vapors through the pumping mechanism.

2. In the process of refrigeration in which a liquid is evaporated in one chamber, the vapors pumped into another chamber and condensed therein at a higher pressure, and then returned to the first chamber at a reduced pressure, the method of lubricating the pumping mechanism which comprises employing a working fluid consisting of a halogen derivative of the methane group and a mineral oil which forms therewith a mechanically inseparable homogeneous mixture, introducing portions of the working fluid into the stream of vapors during their passage to the pumping mechanism and passing the commingled working fluid and vapors through the pumping mechanism.

3. In the process of refrigeration in which a liquid is evaporated in one chamber, the vapors pumped into another chamber and condensed therein at a higher pressure, and then returned to the first chamber at a reduced pressure, the method of lubricating the pumping mechanism which comprises employing a working fluid consisting of ethyl chloride and a mineral oil which forms therewith a mechanically inseparable homogeneous mixture, introducing portions of the working fluid into the stream of vapors during their passage to the pumping mechanism, and passing the commingled working fluid and vapors through the pumping mechanism.

4. In the process of refrigeration in which

a liquid is evaporated in one chamber, the vapors pumped into another chamber and condensed therein at a higher pressure, and then returned to the first chamber at a reduced pressure, the method of lubricating the pumping mechanism which comprises employing a working fluid consisting of a refrigerant and a lubricant which forms therewith a mechanically inseparable homogeneous mixture, collecting a quantity of the working fluid in the path of the vapors to the pump when the pump is idle, drawing into the pumping mechanism such collected fluid upon starting for priming the pumping mechanism, and thereafter introducing portions of the working fluid into the stream of vapors during their passage to the pumping mechanism, and passing the commingled working fluid and vapors through the pumping mechanism.

5. In the process of refrigeration in which a liquid is evaporated in one chamber, the vapors pumped into another chamber and condensed therein at a higher pressure, and then returned to the first chamber at a reduced pressure, the method of lubricating the pumping mechanism which comprises employing a working fluid consisting of ethyl chloride and a mineral oil which forms therewith a mechanically inseparable homogeneous mixture, collecting a quantity of the working fluid in the path of the vapors to the pump when the pump is idle, drawing into the pumping mechanism such collected fluid upon starting for priming the pumping mechanism, and thereafter introducing portions of the working fluid into the stream of vapors during their passage to the pumping mechanism, and passing the commingled working fluid and vapors through the pumping mechanism.

6. In a refrigeration apparatus in which a liquid is evaporated in one chamber, the vapors pumped into another chamber and condensed therein at a higher pressure, then returned to the first chamber at a reduced pressure, the combination with the condensing chamber, of the evaporating chamber, a body of liquid comprising a refrigerant and a lubricant forming therewith a mechanically inseparable homogeneous mixture, conduit means for the passage of vapors from the one chamber to the other chamber, a pump associated with said conduit means for effecting the translation of vapors through said conduit, and means for introducing portions of the liquid into said conduit means at a point intermediate between the vapor inlet and the pump, whereby the commingled vapors and liquid are drawn through the conduit means into the pump and a lubrication of the pump is obtained.

7. In a refrigeration apparatus in which

a liquid is evaporated in one chamber, the vapors pumped into another chamber and condensed therein at a higher pressure, then returned to the first chamber at a reduced pressure, the combination with the condensing chamber, of the evaporating chamber, a body of liquid comprising a refrigerant and a lubricant forming therewith a mechanically inseparable homogeneous liquid, a conduit for the passage of vapors from the one chamber to the other chamber, a pump associated with said conduit for effecting the translation of vapors through said conduit, said conduit extending into and opening adjacent the top of the said one chamber, and means for introducing portions of liquid in the said one chamber into said conduit, at a point intermediate between the vapor inlet and the pump, whereby the commingled vapors and liquid are drawn through the conduit into the pump and a lubrication of the pump is obtained.

8. In a refrigerating apparatus in which a liquid is evaporated in one chamber, the vapors pumped into another chamber and condensed therein at a higher pressure and then returned to the first chamber at a reduced pressure, the combination with the condensing chamber, of the evaporating chamber, a body of liquid comprising a refrigerant and a lubricant forming therewith a homogeneous liquid, conduit means for passage of vapor from the one chamber to the other chamber, and a pump associated with said conduit means for effecting a translation of vapors through said conduit means, said conduit means being provided with an inlet for the admission of vapor and a second inlet for the admission of liquid, whereby the commingled vapor and liquid are drawn through the pump and lubrication of the pump is effected.

9. In a refrigeration apparatus in which a liquid is evaporated in one chamber, the vapors pumped into another chamber and condensed therein at a higher pressure, then returned to the first chamber at a reduced pressure, and in which the liquid employed consists of a refrigerant and a lubricant forming therewith a mechanically inseparable homogeneous liquid, a conduit means for the passage of vapors from the one chamber to the other chamber, a pump associated with said conduit means for effecting the translation of vapors through said means, said conduit means extending into and below any normal operating level of the liquid in said one chamber in return flow formation, the free upper end of the conduit being disposed well above any normal operating level of the liquid in the said one chamber for the reception of vapors, and means for introducing portions of liquid in the said one chamber into said conduit means, whereby the commingled vapors and

liquid are drawn through the conduit means into the pump and a lubrication of the pump is obtained.

10. In a refrigeration apparatus in which a liquid is evaporated in one chamber, the vapors pumped into another chamber, and condensed therein at a higher pressure then returned to the first chamber at a reduced pressure, and in which the liquid employed consists of a refrigerant and a lubricant forming therewith a mechanically inseparable homogeneous liquid, a conduit means for the passage of vapors from the one chamber to the other chamber, and a pump associated with said conduit means for effecting the translation of vapors through said means, said conduit means extending into and below any normal operating level of the liquid in said one chamber in substantially return flow formation, the free upper end of the conduit opening well above the normal operating level of the liquid in the said one chamber for the reception of vapors, said conduit means further having a restricted opening therein below the said normal operating level of the liquid, whereby the commingled vapors and liquid are drawn through the conduit into the pump and a lubrication of the pump is obtained.

11. In a refrigerating machine in which a refrigerant fluid is vaporized, compressed and condensed in a repeating cycle, in combination, a condensing chamber, an expansion chamber, a conduit for the passage of refrigerant liquid from the condensing chamber to the expansion chamber, means associated with said conduit for controlling the distribution of liquid between the said chambers, conduit means for the passage of vapors from the expansion to the condensing chamber, a compressor in said conduit means, said conduit means extending into and below any normal working level of the liquid in the expansion chamber in substantially return flow formation, the free upper end of the conduit opening well above any normal working level of the liquid in the expansion chamber for the reception of vapors, and means for introducing portions of the liquid into the conduit means below the normal working level of the liquid.

12. In the process of refrigeration in which a liquid is evaporated in one chamber, the vapors pumped into another chamber and condensed therein at a higher pressure, and then returned to the first chamber at a reduced pressure, the method of lubricating the working parts of a refrigerating machine which comprises utilizing a working fluid consisting of a refrigerant and a lubricant which readily mix one with the other to form a homogeneous mixture, introducing portions of this working fluid in a liquid state into the refrigerant vapor and passing the commingled liquid working fluid and

refrigerant-vapor through the working parts of the machine.

13. In a refrigerating apparatus, the combination of a condenser, an evaporator, means constituting a path for withdrawing fluid from the evaporator and conveying it to the condenser, and means responsive upon a stoppage of the flow for accumulat-

ing a body of liquid in said withdrawal path, said body of liquid sealing the path ¹⁰ for preventing the back-flow of fluid from the condenser to the evaporator.

In testimony whereof, I have hereunto subscribed my name this 4th day of April, 1922.

ANDREW A. KUCHER.
